(57) **CLAIM**

What is claimed is the original and ornamental design for a regulator, as shown and described.

DESCRIPTION

FIG. 1 is a front view of a regulator.

FIG. 2 is a first side view of the regulator.

FIG. 3 is a rear view of the regulator.

FIG. 4 is a second side view of the regulator.

FIG. 5 is a top view of the regulator.

FIG. 6 is a bottom view of the regulator.

FIG. 7 is a first perspective view of the regulator.

FIG. 8 is a second perspective view of the regulator; and,

FIG. 9 is a third perspective view of the regulator.

The broken lines in the drawings illustrate the unclaimed environment of the regulator and form no part of the claimed design.
